AIR DUCT REGISTER

Ray Derringer, University City, Mo., assignor to International Oil Burner Co., a corporation of Missouri

Application July 22, 1957, Serial No. 673,473

5 Claims. (Cl. 98—106)

This invention relates broadly to air duct registers, and more especially to such registers that are so constructed that the flow of air therethrough may be adjustably controlled.

The invention has among its general objects, the production of a register of the kind described that will be neat and attractive in appearance so as to harmonize with the furnishings or looks of the rooms in which the same may be installed, will be simple in construction and operation, sturdy so as to give a long and useful life without repairs or replacements, economical to make, and will be safe, satisfactory and efficient for use wherever found applicable.

One of the principal objects of my invention is to so construct such a device that it will have a minimum number of parts, and will be adjustably controlled by hand or foot for varying the passage of air therethrough.

Another object of the invention is to so construct said device that the same will have an angularly movable closure plate in connection therewith and as a part thereof, said plate being equally easily manipulated at all positions of placement of the register and regardless of the angularity of the plane in which said device is arranged for mounting.

An added object of my invention is to so construct the mechanism for controlling the opening and closing movement of the closure plate of the device, so that the latter is held safely in all adjusted positions until a subsequent adjustment is desired.

Many other objects and advantages of the construction herein shown and described, and the uses thereof, will be obvious to those skilled in the art to which this invention appertains, as will be more readily and clearly seen from the following description.

In the drawings, wherein like reference numerals represent like or corresponding parts throughout the views,

Figure 1 is a top plan view of the device;

Figure 2 is a end view of the same, with parts broken away and shown in section, showing the closure plate in closed position;

Figure 3 is a cross-sectional view of the device, substantially as taken along the line 3—3 of Fig. 1; and

Figure 4 is another cross-sectional view of the device, taken at right angles to that shown in Fig. 3, along line 4—4 of Fig. 1.

Referring more particularly to the drawings, wherein I have illustrated a preferred embodiment of my invention, there is shown a register adapted to be mounted at an end of a vent, duct or passageway through which a gas such as air, flows, as for instance at the discharge outlet from a room heater or space heater, such vents or outlets being through any suitable wall portion, as for example through one of the side walls or the ceiling, or through the floor.

The mechanism for controlling the passage of air through said vent or duct includes a face member having a face plate 1 that is preferably slightly larger in area than the outlet end of the duct with which it is to be as-

2

sociated, and in the form shown is of generally rectangular shape with its terminal edges extending sufficiently beyond the corresponding terminal edges that bound the duct outlet to permit of using screws or the like for fastening the mechanism at said outlet. The wall through which said duct opens may be any preferred angular position, as for instance, it may be horizontal, vertical, or a plane at an angle that is therebetween.

This plate has an elongated opening 2 therethrough, which in this case is shown as being rectangular so as to conform to the general cross-sectional shape of the duct outlet, and it may have a plurality of vanes or louvers 3—3 bridging across said opening 2, these louvers being so spaced apart as to prevent household articles or toys falling therethrough, or permitting small or relatively sharply pointed shoe heels passing between adjacent louvers.

These vanes or louvers may be made integral with said face plate, or may be otherwise constructed and secured thereto, so as to extend downwardly or rearwardly of the rear face or surface of the face plate. In the instant showing, these louvers are shown as being struck up from a frame 4 that is welded or otherwise firmly secured to the under or rear surface of the face plate. Said frame comprises the base sheet 5 from which said louvers are struck to thereby form the substantially rectangular opening that is substantially coextensive in size and shape with the opening 2, this base sheet having the pairs of opposed spaced-apart upstanding flanges 6—6 and 7—7 extending downwardly or rearwardly therefrom to peripherally surround and bound the opening through said base sheet.

A closure plate 8, also of generally rectangular shape and of a size to substantially entirely close the opening defined by the bounding walls of said frame is mounted at the under or rear portion of the frame, and is hingedly interconnected on and along one edge to one of said upstanding flanges, as by providing longitudinally spaced-apart apertures 9 through one of the longer of the upstanding flanges, as for instance at flange 7, and the adjacent edge of the closure plate is provided with correspondingly spaced-apart prongs or fingers 10 that fit through said apertures with a slight lateral clearance so as to enable said closure plate to be easily and quickly assembled into operative relation to said frame by simply placing said plate with the prongs and apertures in registry and then shifting said plate so that the prongs pass through the cooperating apertures. After the plate has been thus mounted it is obvious that the same may be swung about its hinged edge to vary the angular relationship of the closure plate relative to the frame, so that the passage of air through said register will be controlled according to the degree of said angularity of closing.

A leaf spring, of generally U-shape having a pair of spaced-apart legs 11—11 one of which is preferably longer than the other somewhat as shown, is used to spring-load the closure plate and to resiliently retrieve it after an opening movement of the closure plate, said spring having one of its legs as for instance said longer leg, secured or anchored at its end to the flange 7 of the frame, and the other leg of the spring has its end similarly anchored to said closure plate at a point that is spaced rearwardly from the pivotal axis of the plate. The shorter leg is yieldably actuated lengthwise toward the bight, and its terminal end anchored to said closure plate, to thereby constantly urge and bias the hinged edge of the latter toward the flange 7 to hold the plate in its pivotally mounted position. Obviously, opening of said plate yieldably spreads the spring legs apart, so that upon release of the means holding said plate open, the spring retrieves to its normal position and pulling said plate to closed position.

Now, to control the angular disposition of the closure plate and to enable it to be capable of ready manipulation and operation in all positions of the said plate, I have movably mounted a cam 12 to said face plate, said cam having a tapered or wedge-shaped edge 13 that extends longitudinally therealong in a direction that is transverse to or across the length of the spring and engaging that leg of the latter that is anchored to said flange 7. Thus, the spring is fulcrumed at said flange 7 and has a lever arm whose length is that of the distance between said fulcrum axis and the plane of said wedge-shaped edge of the cam.

Obviously, with both ends of the spring anchored as hereinbefore mentioned, shifting of the element 12 in one direction of its reciprocatory travel will cause the wedge-shaped edge to exert increasing pressure on the spring to swing the latter from its position shown in full lines in Figs. 3 and 4 to that shown in dotted lines therein, transmitting said pressure to said closure plate to swing the latter in unison with said spring. Release of said pressure, by shifting the control means in the reverse direction will permit the closure plate to be urged toward its closed position by the retrieving action of the spring, and will hold said closure plate at the desired position of adjustment.

In order to provide for easy manipulation of said control element, the same may be provided with a stem 14 that projects through a slot 16 formed lengthwise through a portion of said face plate. A knob or button 15 may be fixed at the exposed end of said stem for convenient manipulation of said control element by using the hand or the foot of the user.

When this knob or button is shifted in one direction, by hand or foot, as found most convenient at the time, the wedge-shaped edge of the control element increasingly actuates the spring to adjustably increase the angular disposition of the closure plate to correspondingly increase the air flow outwardly through the register, and when the control member is shifted in the reverse direction, the camming pressure on the spring is correspondingly decreased to permit the spring to yieldably retrieve the closure plate toward its closed position. In this way, the closure plate may be shifted to be fully open, fully shut, or to any intermediate position that controls air flow through the duct, and this closure plate will be yieldably held in all of such spring-loaded adjusted positions, without danger of the plate accidentally shifting from said set positions of adjustment, through vibration or other causes.

I claim:

1. In an air duct register, a face member adapted to cover an end of said duct and is provided with an opening therethrough, a closure plate pivotally hinged along one edge to the rear of said face member and is movable to adjustably angular positions relative to said face member for closing said opening, a bowed spring with opposed legs, the end of one of said legs connected to said face member and the end of its other leg connected to said plate so that said legs resiliently spread apart through opening movement of said plate to retrievably urge the latter to its closed position, and a control element movably mounted on and carried by said member and engaging a spring leg to yieldably adjustably move the latter to transmit movement to the plate to desired angularly disposed positions.

2. In an air duct register, a face member adapted to cover said duct and is provided with an opening, a closure plate hinged to the rear of said face member to be moved to adjustably angular positions relative to said face mem-

ber to close said opening, a substantially U-shaped spring having its leg ends connected to said face member and plate respectively so that opening movement of said plate resiliently spreads said spring legs apart to normally urge said plate toward its closed position, and a control element shiftably slidably carried on said face member and engaging one of said spring legs to movably yieldably actuate said plate to any desired angular disposition.

5 3. In an air duct register, a face member adapted to cover said duct and is provided with an opening therethrough, a closure plate hinged along one edge to the rear of said face member, a substantially U-shaped leaf spring having its leg ends anchored to adjacent portions 15 of said face member and plate so that opening movement of the latter is resiliently resisted by said spring, a slot through said face member, and a control element carried by said face member and reciprocally movable in said slot and having a wedge-shaped edge slidably engageable 20 with said spring to resiliently spread said legs apart to transmit force to said plate to adjustably move and hold the latter to any desired angular disposition.

4. In an air duct register, a face member adapted to cover said duct and having an opening therethrough, a 25 closure plate hinged along one of its edges to the rear of said face member, a U-shaped leaf spring having its leg ends anchored to adjacent portions of said face member and plate and having its legs resiliently spread apart through opening movement of said plate, an elongated 30 slot through a portion of said face member that is spaced from said opening, and a control element carried by said face member and longitudinally movable in said slot and having a wedge-shaped edge slidably engaging said spring to adjustably cam the latter to forcibly move said plate 35 against the resisting spring tension to any desired angular disposition.

5. In an air duct register, a face member adapted to cover said duct and provided with an elongated opening therethrough, a flange element extending rearwardly from 40 said face member and peripherally surrounding the opening to form a frame, a closure plate element at the rear of said flange element, one of said afore-mentioned elements having spaced-apart aligned apertures there-through and said other element having prongs along 45 one edge inserted through said apertures to hinge said plate element to said flange element to permit swinging of said plate element about said one edge, a substantially U-shaped spring extending transversely across said face member opening and having one leg connected to said 50 face member and having its other leg connected to said closure plate at a point spaced rearwardly of said one edge, one leg of said spring constantly urging said closure plate toward said face member to urge said prongs through said apertures to interlock said face member and closure plate and yieldably urge the latter to its closed 55 position, and a control slidably carried by said face member and having a wedge portion transversely engageable with one of said spring legs to transmit force to the latter and control separation of said legs on slidable 60 movement of said control to adjustably yieldably move said closure plate element to any desired angular disposition of its swing.
